UNITED STATES PATENT OFFICE.

HENRY A. HOUSE, JR., OF SPRINGFIELD, MASSACHUSETTS, ASSIGNOR TO WIRE WHEEL CORPORATION OF AMERICA, OF BUFFALO, NEW YORK, A CORPORATION OF NEW YORK.

METHOD OF FORMING NIPPLE SOCKETS IN WHEEL RIMS.

Application filed September 4, 1918, Serial No. 252,672. Renewed April 4, 1923.

To all whom it may concern:

Be it known that I, HENRY A. HOUSE, Jr., a citizen of the United States, residing in Springfield, in the county of Hampden and State of Massachusetts, have invented certain new and useful Improvements in the Methods of Forming Nipple Sockets in Wheel Rims; and I do hereby declare the following to be a full, clear, and exact description of the same, such as will enable others skilled in the art to which it appertains to make and use the same, reference being had to the accompanying drawings, and to figures of reference marked thereon, which form part of this specification.

Like figures of reference refer to like parts.

This invention relates to methods of forming nipple sockets in wheel rims.

One object of this invention is to provide a method of forming sockets in wheel rims, without machining the same.

Another object is to form nipple sockets having angular depressions or seats for nipple heads, which shall resist the turning of the nipple when seated thereon.

My invention consists in carrying out certain operations upon any suitable devices, in the development of nipple sockets.

A set of devices adapted for such development is illustrated in the drawings, the operations are explained and what I claim is set forth.

In the drawings:

Figure 1 is a front elevation of part of a press used in the first operation of forming the sockets in the rim.

Figure 2 is a sectional side elevation of the parts shown in Figure 1.

Figure 3 is a plan of the parts shown in Figures 1 and 2.

Figure 4 is a fragment of wheel rim showing the grouping of the nipple sockets after the first operation.

Figure 5 is a longitudinal section of a hemispherical pocket formed in the first operation.

Figure 6 is a front elevation of parts of the device used in carrying out the second step of my method.

Figure 7 is a sectional side elevation of the parts shown in Figure 6.

Figure 8 is an enlarged sectional elevation of a finished socket, including the forming and punching dies. 55

Figure 9 is a perspective view of the forming end of a hollow punch.

Figure 10 is a plan view of a fragment of rim, showing the finished nipple socket.

In the figures, referring particularly to Figures 1, 2, and 3, upon the horn 1, of a pressing machine not shown, is fixed an impression block 2, having hemispherical pits 3, 3, 3, into which is sunk the metal of the rim 4, by means of the punches 5, 5, 5, 65 which are in sliding engagement with the guide block 6. Upon bracket 7, is adjustably fixed a block 8, in sliding engagement therewith, but fixed in position by the set screw 9. Projecting up from the block 8, is a cylindrical piece 10, which engages a reciprocating guide pin 11, spring-pressed downward by the spring 12, which bears against an adjusting screw 13. In Figure 3 are shown three impression punches 5, 5, 5, 75 passing through holes A, B, and C, in a guide block 6. In Figure 4 are shown two rows of hemispherical pockets, marked respectively D and E, there being twice as many pockets in the row D as there are in 80 the row E. One of the pockets is shown in section in Figure 5.

Referring to Figures 6 and 7, eccentrically mounted and inclined in position on parts of a forming and punching press, is a rim 4, 85 having two rows of hemispherical pockets, previously punched therein. The rim 4 hangs upon a forming and punching die 14, resting upon a horn 15, of the press. The rim 4 is shown resting upon an inclined plate 16, which is supported upon brackets 17 and 18. The rim 4 is also supported against pins 19 and 20, fixed to the plate 16. In Figure 8, the bottom of the hemispherical pocket is shown formed into a pyramidal 95 socket, by means of the hollow punch 21, shown resting thereon. A cylindrical punch 22 is in sliding engagement with the punch 21, which forms the hole 23, in the socket. In Figure 9, the hollow punch 21, is shown 100 having a four flat-sided end 24, and a hole 25. In Figure 10, a hemispherical pocket 26, is shown having a polygonal and angularly depressed socket 27.

With the devices as herein illustrated and above described, my method of forming nipple sockets is as follows:

To begin with, a rim 4, is hung upon the block 2, and the three hemispherical ended punches 5, 5, 5, occupying the holes A, B and C, in the guide 6, are forced down upon the rim 4, causing the metal thereof to sink into pits 3, 3, 3, and form hemispherical pockets like that shown in Figures 4 and 5. Two of the pockets are adjacent to one flange, and one is adjacent to the other flange of the rim 4. The punches are next raised and the rim 4 is turned, so that the guide pin 11, rests in one of the pockets previously formed, the pin 11 having previously been properly positioned by so setting the block 8, as to give the desired spacing to sets of pockets punched. After completing the formation of hemispherical pockets in the rim, the same is taken to the socket forming and hole punching machine, parts of which are shown in Figures 6 and 7.

The rim 4 is placed upon the plate 16, and hung upon the block 14, having the convex side of the pocket resting in a specially formed pit 14^a, having a hole 14^b, for co-operation with the punching pin 14^c.

The spokes of a wire wheel make various angles with the rim as they connect with the hub of the wheel, but they may be grouped according to the angle at which they stand.

The socket forming and punching machine has its parts so made and arranged as to form sockets suited to a given group of spokes.

The pit in the block 14, is positioned so that the center of a pocket resting thereon, is on or near the axis of the punch or forming die. The socket forming die is then

driven down marking the inner wall of a depression by forming a socket of the desired shape, and next the punch is driven down forming the hole in the socket.

Any form of end may be provided in the socket forming die and a corresponding shaped pit used in the block if it marks the inner wall of the depression.

If the angle at which the axis of the socket is to stand in the rim is not much from the radial direction, then the first operation of making hemispherical pockets may be dispensed with and the socket may be formed as the first operation, and the punching of the hole as the second.

Having described my invention I claim,

1. The method of treating metal rims for wire spoked wheels in which the spokes are inclined at various angles, consisting in, first forming hemispherical indentations by a punch operating at right angles to the surface of the rim, second reshaping a portion of the inner wall of the depression by a pyramidal punch operating at an angle to the surface of the rim other than a right angle and third, perforating said depression at the center of the reshaped portion by a punch operating at the same angle as the pyramidal punch.

2. The method of treating metal rims for wire wheels in which the spokes are inclined at various angles consisting in first, forming hemispherical depressions by a punch operating at right angles to the surface of the rim, second, marking the inner walls of each depression and third, perforating each of said depressions by a punch operating in the line in which the spoke to be inserted will extend.

HENRY A. HOUSE, JR.
